UNITED STATES PATENT OFFICE

110,784

DESIGN FOR A DRESS

Jacob M. Sterngold, New York, N. Y.

Application July 14, 1938, Serial No. 78,458

Term of patent 3½ years

To all whom it may concern:

Be it known that I, Jacob M. Sterngold, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged view of one of the appliquéd motifs.

The characteristic feature of my design resides in the combination on the dress disclosed of the specific appliquéd on the front panel of the dress in association with the specific button trim as shown.

I claim:

The ornamental design for a dress, substantially as shown and described.

JACOB M. STERNGOLD.
